MATTRESS AND CUSHION VIBRATOR

Samuel L. McNair, Overland Park, Kans., assignor to The
Songrand Corporation, a corporation of Missouri

Filed Feb. 21, 1966, Ser. No. 1,132

Term of patent 14 years

(Cl. D83—1)

*Fig. 1.**Fig. 2.**Fig. 3.*

Fig. 4.

Fig. 5.

Fig. 6.

Fig. 7.

FIG. 1 is a top plan view of a mattress and cushion vibrator according to the invention;

FIG. 2 is a side elevational view of same; the other side is substantially the same as this side;

FIG. 3 is a sectional view of same, being taken along the line 3—3 of FIG. 2 in the direction of the arrows;

FIG. 4 is an end elevational view of same;

FIG. 5 is another end elevational view of same;

FIG. 6 is an enlarged, fragmentary side elevational view of the housing at the upper end; and

FIG. 7 is an enlarged fragmentary sectional view taken along the line 7—7 of FIG. 6 in the direction of the arrows.

I claim:

The ornamental design for a mattress and cushion vibrator, as shown and described.
